PORTABLE CUTTER FOR KEYWAYS

Walter H. Johnson, 4683 Park Heights Ave., Baltimore 15, Md., and Samuel M. Keenan, Box 203, Rte. 1, Race Road, Hanover, Md.

Filed Sept. 28, 1959, Ser. No. 842,955

1 Claim. (Cl. 90—12)

The present invention relates to portable cutters for keyways of the type used in shafts.

The primary object of the invention is to provide a portable keyway cutter for shafts which can be utilized without removing the shaft from its support.

Another object of the invention is to provide a portable keyway cutter of the class described above with which both longitudinally extending keyways and Woodruff keyways can be cut without the necessity of making mechanical changes in the apparatus.

A further object of the invention is to provide a portable keyway cutter of the class described above which is fully adjustable to permit its use over a wide range of key sizes.

A still further object of the invention is to provide a keyway cutter of the class described above provided with interchangeable means to permit keyways to be cut in a plurality of shafts of different diameters.

Another object of the invention is to provide a portable keyway cutter of the class described above which is inexpensive to manufacture, simple to use and which reduces the labor required for cutting keyways in shafts to a minimum.

Other objects and advantages will become apparent in the following specification when considered in light of the attached drawings, in which:

FIGURE 1 is a perspective view of the invention;

FIGURE 2 is a fragmentary vertical sectional view taken along the line 2—2 of FIGURE 1, looking in the direction of the arrows;

FIGURE 3 is a transverse sectional view taken along the line 3—3 of FIGURE 1, looking in the direction of the arrows;

FIGURE 4 is a fragmentary bottom plan view of the invention;

FIGURE 5 is a fragmentary front elevation of the invention; and

FIGURE 6 is a perspective view of one of the interchangeable bushings shown removed from the keyway cutter.

Referring now to the drawings in detail wherein like reference characters indicate like parts throughout the several figures, the reference numeral 10 indicates generally a portable keyway cutter constructed in accordance with the invention.

The portable keyway cutter 10 includes an elongated body 11 having a semi-cylindrical enlarged head 12 integrally formed on one end thereof. The head 12 is downwardly offset from the body 11, as can be clearly seen in FIGURE 2.

The upper surface of the body 11 is relatively straight and is provided with an elongated dove-tail tongue 13.

The body 11 at the end thereof opposite the head 12 is provided with an upstanding boss 14 arranged in oppositely extending relation with respect to the head 12. A transverse cylindrical bore 15 extends through the head 12 and has one side thereof intersecting the peripheral surface of the head 12 delineating a pair of spaced parallel edges 16, 17, as can be clearly seen in FIGURES 1 and 5. The head 12 has a generally rectangular keyway 18 formed therein within the bore 15 in opposed relation to the edges 16, 17, as is illustrated in FIGURE 2.

A worm-drive member 19 is journaled in the head 12

2

with its axis parallel to the axis of the bore 15 with the drive member 19 extending into the bore 15. A shaft 20 is rigidly secured to one end of the drive member 19 and extends therefrom through the head 12 and outwardly therebeyond. A knob 21 is mounted on the outer end of the shaft 20 to permit the shaft 20 and the drive member 19 to be rotated thereby.

An adapter bushing, generally indicated at 22, has a generally cylindrical external face 23 and a cylindrical internal bore 24 arranged eccentrically to the external face 23 with their axes parallel. The internal bore 24 intersects the external face 23 to form a pair of spaced parallel edges 25, 26.

The adapter bushing 22 has a concave threaded groove 27 formed in the generally cylindrical external surface 23 generally oppositely of the edges 25, 26. A generally rectangular keyway 28 is also formed in the adapter bushing 22 through the cylindrical outer surface 23 adjacent and parallel to the threaded groove 27. A pair of threaded set screw bores 29 extend transversely through the adapter bushing 22 intersecting the generally cylindrical bore 24. A set screw 30 is threaded into each of the bores 29, for reasons to be assigned.

The adapter bushing 22 is mounted for longitudinal sliding movement in the bore 15 of the head 12 and a rectangular key 31 extends into both the keyway 18 in the head 12 and the keyway 28 in the bushing 22, preventing relative rotation between the bushing 22 and the head 12. The drive member 19 in the head 12 extends into the threaded groove 27 in the adapter bushing 22 so that rotation of the drive member 19 will slide the adapter bushing 22 longitudinally of the bore 15.

A carriage 32 is provided with an elongated dove-tail slot 33 arranged in longitudinal sliding engagement over the dove-tail tongue 13 on the body 11. The carriage 32 has a threaded bore 34 arranged centrally therein and extending parallel to the dove-tail groove 33. A threaded shaft 35 is threaded into the threaded bore 34 and is journaled for rotation in the upstanding boss 14. A hand crank 36 is secured to the outboard end of the threaded shaft 35 so that the shaft 35 may be rotated by hand. Rotation of the shaft 35 causes relative sliding movement between the carriage 32 and the body 11.

The carriage 32 at the end thereof opposite the boss 14 is provided with a pair of blocks 37, 38 arranged in spaced apart parallel relation and integrally formed with the carriage 32. The block 38 is offset toward the cylindrical head 12 beyond the confines of the body 11. A shaft 39 is journaled in the block 37 with one end 40 thereof terminating in engagement with the adjacent face 50 of the block 38. A gear 41 is fixed to the opposite end of the shaft 39 adjacent the opposite side of the block 37. A cutter shaft 42 is journaled in the block 38 in axial alignment with the shaft 39 and has a reduced end portion 43 thereof secured in a socket 44 in the shaft 39 by means of a set screw 45. The shaft 42 has a circular cutter 46 integrally secured to the end thereof opposite the reduced end portion 43 and arranged in aligned relation intermediate the edges 25, 26 and the edges 16, 17.

A circular housing 47 is secured to the carriage 32 oppositely of the block 38 and has a plurality of radially inwardly extending set screws 48 threaded therethrough. An electric motor 49 extends into the housing 47 and is clamped therein by the set screws 48. A gear 50 is mounted on the electric motor 49 and meshes with the gear 41 so that rotation of the motor 49 will rotate the cutter 46.

In the use and operation of the invention, a cylindrical shaft 51 is to be provided with a keyway and the adapter bushing 22 is slipped over the end thereof and clamped thereto with the set screws 30. The head 12 is then engaged over the adapter bushing 22 and adjusted

with respect thereto with the knob 21. The cutter 46 is then rotated by means of the electric motor 49 and the carriage 32 is adjusted with the hand crank 36 to bring the cutter 46 into cutting engagement with the shaft 51.

In cutting a Woodruff key the cutter 46 is moved by means of the carriage 32 into the shaft while the head 12 remains stationary with respect to the adapter bushing 22. The cutter 46 is then moved directly out of the shaft 51, resulting in a semi-circular key receiving groove of the Woodruff type.

In forming rectangular keyways in the shaft 51, the cutter 46 is moved into the shaft 51 to the desired depth by use of the hand crank 36. The cutter 46 is then moved longitudinally of the shaft 51 by rotation of the handle knob 21 so as to rotate the drive member 19 with respect to the adapter bushing 22. The head 12 and the carriage 32 are moved longitudinally of the shaft 51 to the desired extent or until their limit of movement has been reached. If a longer keyway is desired the adapter bushing 22 is moved longitudinally of the shaft 51 and re-clamped thereto with the cutter 46 in aligned relation to the slot already cut.

In the event that a different diameter shaft is to have a keyway cut therein, a separate adapter bushing 22 having an internal bore 24 of the desired diameter is used in the head 12. It should also be understood that the cutter 46 may be interchanged to provide the desired circumference and width of cut when forming different keyways.

Having thus described the preferred embodiment of the invention, it should be understood that numerous structural modifications and adaptations may be resorted to without departing from the scope of the appended claim.

What is claimed:

A portable keyway cutter comprising an elongated body

having a semi-cylindrical enlarged head, said body having an elongated dove-tail tongue thereon and said head having a transverse cylindrical bore with a slot in the side thereof, said bore having a longitudinally extending keyway therein, a worm gear journaled transversely in said head intersecting said bore, an adapter bushing substantially crescent-shaped in cross section, and having a keyway therein aligned with said first-mentioned keyway, seated in said bore, a key in said keyways, said adaptor having a threaded channel in the outer surface thereof co-acting with said worm for adjustment of said adaptor transversely of said head, said adaptor also having an elongated slot aligned with said side slot, an elongated carriage having a dove-tail groove mounted on said dove-tail tongue for longitudinal movement relative to said body, said carriage having a threaded bore in one end thereof, a tongue on the end of said body having a bore therein aligned with said threaded bore, a screw extended through said bore in said tongue and engaging in said threaded bore for longitudinal movement of said carriage relative to said body, said carriage having a slot in its other end and a perpendicular bore intersecting said slot, a shaft rotatably mounted in said perpendicular bore, motor means mounted on said carriage for driving said shaft, and a cutter removably mounted on said shaft in line with said slots in said bore and said adaptor.
